ROY H. BELL AND FRED R. SEARLES, OF GREAT FALLS, MONTANA.

SUPPORT FOR WRITING TABLETS AND THE LIKE.

Application filed August 26, 1924. Serial No. 734,267.

This invention relates to an adjustable card or tablet holder or support for use as an attachment on cash registers, adding machines, or similar articles of store furniture.

5 In many lines of retail merchandising it is customary to have the business transaction completed at the sales counter, including the making of a written memorandum of the sale and an adding machine or cash register 10 record incident to the payment. In stores where the sales are of small individual amounts but large in number the efficiency and accuracy of the salesman is promoted greatly by providing a simple and systematic 15 means for making a printed memorandum in conjunction with the sale and its payment. It is essential that this means for making the memorandum be convenient of use and occasion the least possible interference with the display of merchandise or the 20 use of the counter.

One of the objects of our invention is to provide a convenient, inexpensive, quickly and easily attachable and adjustable device 25 for use in conjunction with cash registers, adding machines, or the like, whereby cards, tablets or other memorandum pads of similar nature are held for the ready use of the salesman. It is especially useful for the 30 tabulation and segregation of department sales and for other memoranda and notes in stores, resulting in a great saving of time and increasing the accuracy and efficiency of the clerks, while at the same time permitting 35 the use of the counter space beneath for the display of merchandise or for other purposes.

The above and other advantages will be 40 readily apparent from the following description of one form of our invention in which—

Figure 1 is a perspective view of the support as applied to a conventional cash register;

Fig. 2 is a plan view of the bracket;

Fig. 3 is a side elevation of the same;

Fig. 4 is a cross section on the line 4—4 in Fig. 2;

Fig. 5 is a plan view of card holder;

Fig. 6 is a cross section on the line 6—6 of Fig. 5;

Fig. 7 is a plan view of a modified form of card holder;

Fig. 8 is a cross section on the line 8—8 in Fig. 7;

Fig. 9 is a cross section on the line 9—9 in Fig. 7; and

Fig. 10 is a similar cross section of a modified clip.

Generally speaking, our improvement consists in providing a plurality of article holding leaves supported upon an adjustable and removable bracket member which in turn is carried by conventional store furniture. In Fig. 1, there is shown such a bracket 10 adapted to be mounted upon a cash register 50 shown in outline at 50. The bracket 10 carries opposed extensions 11 adapted to insure the bracket 10 remaining in its predetermined position upon the supporting article. One end of the bracket 10 is twisted out of 60 plane of the projections 11 to form a portion 12 shown in Fig. 3. A strap 13 which may be integral with 12 extends from the end of the latter in a direction parallel to 10 and has a projection 14 resting upon a part of 70 the supporting structure. A sleeve 15 is provided as indicated at Figs. 1 and 4 to receive the inner end of the bracket 10. The sleeve 15 and the bracket 10 are each drilled to receive screws or machine bolts 16 by 80 which the bracket is fixably attached in an adjustable manner to the cash register 50. An article holder 17 is mounted on bracket 10. The platform of the latter is generally provided with screws adapted to be used in 85 the manner indicated by 16. Strap 13 may be omitted.

The portion 12 of bracket is given a convenient slope from the horizontal by means of the length of strap 13 so that it will form 90 a convenient shelf upon which to write. A plurality of leaves are mounted upon the portion 12 in the manner indicated in Figs. 1 and 6. The uppermost leaf 18 has inturned edges on three of its four sides whereby 95 memorandum sheets, blank pads, cards or tablet pads will be conveniently held during use. One side edge of the leaf 18 has down-turned ears 19 which form leaves of the hinge 20.

The lower shelf or leaf 21 is riveted, bolted or otherwise attached to the bracket 10 and its portion 12. In like manner, this leaf has in-turned edges. Straps 22 extend from one side of the leaf 21 and are offset 105 downwardly to constitute a part of hinge 20. One or more fingers 23 are also extended downwardly at right angles from the leaf 21 beyond the hinge 20.

As indicated in Fig. 6, the upper leaf 18 110 is supported on the in-turned edges of the lower leaf 21 while the straps 19 are offset

to lie above the straps 22. Rotation of the leaf 18 around hinge 20 will permit the leaf to take an inverted horizontal position as shown in Fig. 6 and thus provide that its rear surface forms a writing surface, it being evident that the member is rigidly supported in this position by means of the depending fingers 23. Suitable means may be adapted to this rear surface to hold the desired writing materials.

The bracket 12 is inclined rearwardly along the side of the cash register or other support whereby the leaves are held at an inclination suitable for writing purposes. Preferably, the entire bracket, that is the inclined portion 12, and the front and rear extensions are made from a single casting, the inclination of the portion 12 being obtained by twisting the material at the junction of said portion and the forward extension 10. To minimize the space occupied by the holder, especially when the article holder leaves are open, all of the leaves are hinged at the same side of the bracket and all can be opened in a direction only away from the support. This permits the inclined portion 12 to be positioned close against the side of the support.

In Figs. 7, 8 and 9 a modification has been shown in which the lower shelf 23' has a plane surface except for a spring clip 24 adapted to hold a pad of paper 25 or the like. The upper leaf 26 has the hinge straps 19 and also opposite supporting feet 27 maintaining the leaves 26 and 23 in parallel relation. The leaf 26 is adapted to be pivoted to the hinge 20 into a vertical position as indicated.

Numerous other forms of holding means may be used such as the reversely turned supporting clip 28 in Fig. 10.

The device above described is readily attached to the customary articles of store furniture, as for example cash registers, and forms a rigid support for a writing tablet or the like. By means of sleeve 15 the bracket is adapted to be fitted to articles of varying widths. The plurality of leaves provide room upon which separate series of memoranda may be entered as the case may demand, the upper leaf being pivoted around the point 20 for the entry of notes upon the lower leaf or upon the reverse of the upper leaf. It will be evident that great variation may occur in the form of paper

holder adapted and the in-turned edges may be rolled, crimped, or otherwise treated. Sufficient space is left between the leaves to permit the use of efficient spring clips where desired. While we have shown one form in which our invention may be embodied, it will be obvious that numerous changes in minor details may be made without departing from the scope of the appended claims.

What is claimed is:

1. A device of the character described comprising a flat strip having a pair of arms extending laterally from one edge at opposite ends thereof to form a supporting bracket, one arm being extended upwardly and then laterally to form a supporting hanger having its end portion lying in a plane making an acute angle with the plane of the strip, the other arm having its end portion twisted to lie in a plane parallel to but below that in which the end portion of the first arm is disposed, and an article holder mounted on the strip.

2. A device of the character described comprising a flat strip having a pair of arms extending laterally from one edge at opposite ends thereof to form a supporting bracket, one arm being extended upwardly and then laterally to form a supporting hanger having its end portion lying in a plane making an acute angle with the plane of the strip, the other arm having its end portion twisted to lie in a plane parallel to but below that in which the end portion of the first arm is disposed, an article holder secured to said strip, and a second holder hinged to the edge of the first holder.

3. A device of the character described comprising a flat strip having a pair of arms extending laterally from one edge at opposite ends thereof to form a supporting bracket, one arm being extended upwardly and then laterally to form a supporting hanger having its end portion lying in a plane making an acute angle with the plane of the strip, the other arm having its end portion twisted to lie in a plane parallel to but below that in which the end portion of the first arm is disposed, a bracket secured to a support and receiving the last mentioned arm, and an article holder mounted on said strip.
